UNITED STATES PATENT OFFICE

GROVER D. LEISTER, OF SAN FRANCISCO, CALIFORNIA

PORTABLE GIN POLE STRUCTURE

Application filed May 1, 1929. Serial No. 359,538.

This invention relates to improvements in construction apparatus, and more particularly to what may be termed a hoisting apparatus or gin pole structure.

It is at present the practice in setting poles by telephone and electric light companies to make an excavation, transport the pole in proximity thereto, erect a gin pole near the excavation and by the aid of the gin pole to erect the pole desired. The setting up and taking down of the gin pole consumes considerable time, in fact requires more time than does the actual setting of the pole.

It is to expedite the setting of such pole structures that the present invention is designed to accomplish, and the invention has for its objects to provide a portable gin pole structure mounted on the side of a vehicle and capable of being easily manipulated for erection near the point where the regular pole is to be set.

A further object is to provide a gin pole on a portable apparatus which is adapted for ready movement to and from operative and inoperative position, enabling the vehicle mounting the pole to be readily driven from point to point, and to conform to the clearing laws of the various motor vehicle acts.

30. A further object is to provide a structure wherein when the gin pole is set up, means are provided for relieving the vehicle of the longitudinal load placed on the gin pole, and at the same time provide a foot or base for the latter.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages of the invention.

To more clearly comprehend the invention, reference is directed to the accompanying drawings, wherein—

Figure 1 is a view in side elevation of the preferred embodiment of my invention, with the gin pole in lowered or inoperative position.

Figure 2 is a view in side elevation of the rear portion of the vehicle with the gin pole tilted to vertical, operative position, and the pole to be set supported by the tackle thereof.

Figure 3 is a view in rear end elevation of the structure illustrated in Figure 2.

In the drawings, 1 indicates a vehicle, preferably in the form of a truck, to the rear end and at one side of the chassis of which is mounted a frame consisting of the vertical frame member 2, the diagonal cross brace 3 and the forwardly extending brace 4, this structure being illustrated as formed of angle members; it being necessary that it be particularly rigid, due to the work to be performed thereby, but may be made removable, if desired.

Through the upper end of the member 2 extends a fulcrum pin 5 disposed in a horizontal plane, substantially transversely of the chassis 1. The pin 5 extends through a suitable gin pole 6 of a length when moved to operative position so that its upper end will project some distance above the upper end of the member 2, and its lower end will lie in close proximity to the ground or supporting surface for the wheels 7 of the vehicle 1. While this gin pole structure is not necessarily centrally fulcrumed, the same is constructed as to be substantially balanced on either side of the pin 5 by reason of the bottom portion being thicker and therefore heavier than the top portion. At its upper end, the gin pole carries tackle 8, and at its lower end mounts guide brackets 9, within which slide the main portion 10 of a supporting foot 11, held in its adjusted position by lock pins or other means 12 passing through the members 9 and 10.

It will be observed that with the foot 11 resting on the support therefor, and the pins 12 in interlocking relation, the wheel 7 and the vehicle will be relieved of the load placed on the gin pole 6 when the same is in vertical or operative position.

It will be readily observed that the gin pole structure is capable of being quickly set up and taken down and transported from point to point with extremely little effort; also that the gin pole 6 may be swung either forwardly or rearwardly on pivot 5, and if it is desired to swing the top portion a considerable distance rearwardly, the gin pole structure should be mounted on a chassis 10 whose body extends beyond the wheel 7; also that the same is always ready for operation, and when the pole is lowered, as in Figure 1, the over-all height of the apparatus is no greater than that of the conventional truck.

To insure the gin pole 6 being held in vertical position and to prevent its tipping or pivoting when a load is placed on the tackle 8 thereof, I mount a chain 13 on the angle plate 14, the chain being of sufficient length to wrap around the gin pole 6, and the end thereof engage an eye 15. This structure is effective, cheap and capable of being quickly manipulated when desired.

I claim:—

1. A portable gin pole structure comprising a vehicle; a frame extending upwardly therefrom and at one side thereof, a gin pole pivoted to the frame beyond the vehicle side 30 for swinging movement into a vertical position, and tackle operatively associated with one end of the gin pole.

2. A portable gin pole structure comprising a vehicle, a frame extending upwardly 35 therefrom and having an upright portion arranged at a side of the vehicle, a gin pole pivoted to the upright portion of the frame for swinging movement on a horizontal axis to and from a vertical position, and tackle 40 associated with one end of the gin pole.

3. A portable gin pole structure comprising a vehicle, a gin pole carried thereby and at one side thereof and adapted for swinging movement from an inoperative position to 45 a vertical operative position, tackle associated with one end of the gin pole, and means for relieving the vehicle of the longitudinal load placed on the gin pole when in vertically operative position.

50 4. A portable gin pole structure comprising a vehicle, a frame carried thereby and extending upwardly therefrom at one side, and having lateral supports for the upright portion, a gin pole pivotally mounted on said frame to swing on a horizontal axis disposed transversely of the vehicle with the free ends of the pole substantially balanced on the pivot, tackle associated with one end of the gin pole, and an adjustable extension at the 55 other end of said pole.

5. A portable gin pole structure comprising a vehicle, a gin pole carried thereby at one side thereof and adapted for swinging movement from an inoperative position to a 60 vertical operative position, tackle associated

with one end of the gin pole, means for relieving the vehicle of the longitudinal load placed on the gin pole when in vertical operative position, and means for releasably locking the gin pole in vertical operative position to prevent the same from pivoting relative to the vehicle.

In testimony whereof I have signed my name to this specification.
